[57] **CLAIM**

The ornamental design for a diaper, as shown and described.

DESCRIPTION

FIG. 1 is a front perspective view of a diaper, showing our new design in assembled condition;

FIG. 2 is a bottom plan view thereof;

FIG. 3 is a rear perspective view thereof;

FIG. 4 is a front perspective view of a second embodiment of the diaper, with the only difference residing in the fabric and all other views being identical to that shown in FIGS. 1-3 and 5; and,

FIG. 5 is an elevational view thereof, in disassembled condition, with the opposite side being plain and unornamented.

FIG. 1

FIG. 2

FIG. 3

FIG. 4

FIG. 5
